UNITED STATES PATENT OFFICE.

CHARLES EDWARD HAVILAND, OF LIMOGES, FRANCE.

DESIGN FOR A CUP.

SPECIFICATION forming part of Design No. 27,378, dated July 20, 1897.

Application filed June 5, 1897. Serial No. 639,610. Term of patent 7 years.

To all whom it may concern:

Be it known that I, CHARLES EDWARD HAVILAND, a citizen of the United States, residing at the city of Limoges, in the Republic of France, have invented and produced a new and original Design for a Cup or Similar Article of a Table-Service, of which the following is a specification, reference being had to the accompanying drawings, forming part thereof, and in which—

Figure 1 is a side elevation of a cup bearing my design, and Fig. 2 is a sectional view of same on the dotted line 2 2 of Fig. 1.

The leading features of my design consist of the shape of the body of the cup or similar article of a table-service and the ornamental configuration thereon, substantially as shown, without regard to the handle A, which forms no absolutely essential part of the design.

The sides of the cup comprise the two substantially vertical bands B C, the latter being broader than the upper band and termi-

nating in a rather sharp lower edge D, whence the bottom E of the cup inclines inward and downward on graceful lines to a base F. The upper band B at its lower edge merges into the lower band C on a well-defined line G, and said band bears the surface ornamentation H and also at definite points the ornamental scroll figures I, whose lower portions extend downward on the band C. The lower band C bears the scalloped ornamental scroll figure J, in the form of loops hanging from the lower edge G of the upper band B.

What I claim is—

The design for a cup or similar article of a table-service, substantially as shown and described.

Signed at Limoges, in the Republic of France, this 13th day of May, A. D. 1897.

CHARLES EDWARD HAVILAND.
